United States Patent Office

Des. 203,150
Patented Dec. 14, 1965

203,150

COUNTER TOP DRINK DISPENSER

Jack J. Booth and William C. Branch, both of
P.O. Box 10872, Dallas, Tex.

Filed July 14, 1964, Ser. No. 80,878

Term of patent 14 years

(Cl. D2—3)

FIG. 1 is a perspective view of the counter top drink dispenser as viewed from the service side; and

FIG. 2 is a perspective view of the counter top drink dispenser as viewed from the top and customer side.

The undisclosed side of the counter top drink dispenser is substantially the same in appearance as the side shown.

We claim:

The ornamental design for a counter top drink dispenser, as shown and described.
